CHANGE MAKING AND DELIVERING
DEVICE

Morris Dorman, Baltimore, Md.

Application March 2, 1934, Serial No. 713,737

12 Claims. (Cl. 194—91)

This invention relates to a change making and delivering device designed primarily for use in connection with coin controlled article vending machines, but it is to be understood that the device may be employed independently or in any connection for which it may be found applicable, and the invention has for its primary object to provide, in a manner as hereinafter set forth, a manually operable device of the class referred to for making and for delivering therefrom, within convenient reach, of the necessary change, when a coin of greater value than the sale price of the article to be vended has been inserted in the device.

15 A further object of the invention is to provide, in a manner as hereinafter set forth, a device of the class referred to including means for delivering therefrom, an inserted coin of greater value than the cost of the article to be vended, when the device is empty of the coins which are required in the making of change.

Further objects of the invention are to provide, in a manner as hereinafter set forth, a device of the class referred to which is comparatively simple in its construction and arrangement for obtaining the purpose sought thereby, strong, durable, compact, readily assembled, conveniently operated, and comparatively inexpensive to set up.

To the above ends essentially, and to others which may hereinafter appear, the invention consists of such parts, and such combination of parts as fall within the scope of the invention as claimed.

In the drawings:

35 Figure 1 is a side elevation of the device.

Figure 2 is a plan view of the device, taken on a plane parallel to the base plate.

Figure 3 is an end elevation showing the upper part of the higher end of the device on a plane perpendicular to Figure 2.

Figure 4 is a view similar to Figure 3 but showing the opposite end of the device and the bottom of the front support.

Figure 5 is a detail section on the line 5—5 of Figure 2.

Figure 6 is a detail section on the line 6—6 of Figure 2.

Figure 7 is a detail section on the line 7—7 of Figure 2.

50 Figure 8 is a section on the line 8—8 of Figure 7.

Figure 9 is a section on the line 9—9 of Figure 7.

Figure 10 is a section on the line 10—10 of Figure 7.

Figure 11 is a detail plane of the change deliverer shown in Figure 9.

Figure 12 is a detail plane of the change deliverer shown in Figure 10.

Figure 13 is a section on the line 13—13 of 5 Figure 2.

Figure 14 is a detail view from the right of Figure 13 showing the carriage and elevator forming elements of the inserted coin expelling mechanism.

10 Figure 15 is a section on the line 15—15 of Figure 14.

Figure 16 is a section on the line 16—16 of Figure 15.

15 Figure 17 is a face view of the coin supporting plate forming an element of the inserted coin expelling mechanism.

Figure 18 is a top plan of the combined coin gripping elevator lowering and carriage shifting arm of the expelling mechanism.

20 Figure 19 is a plan view of a portion of the coin chute and showing the means used to discard therefrom one cent pieces.

Figure 20 is an elevation of the parts shown in Figure 19 from the right side of that figure.

25 Figure 21 is a section on the line 21—21 of Figure 19.

Figure 22 is a schematic view of the several coin supporting plates and pushers.

30 Figure 23 is a view of the change delivering and inserted coin chutes and further showing the arrangement in dotted line of the openings through which the change drops into the change delivering chute.

Figure 24 is a reduced perspective view of a 35 housing for the device.

The invention in its broadest aspects is for the purpose of delivering the correct amount of change required between a coin of greater value and the sale or vending price of an article of 40 merchandise. The device, is illustrated by way of example, for accurately making change between a coin of greater value and a five cent sale or vending price for the article. The arrangement of the various elements of the device, 45 to be hereinafter specifically described, is such that after a half dollar or a quarter or a dime has been inserted in the device, the latter when operated will deliver change consisting of a quarter and four nickles or four nickels or one nickel 50 respectively.

With reference to Figures 1 and 3, the device has as a part thereof a vertically disposed rear support 1 of the desired height and of skeleton form. The support is formed with a pair of 55

upstanding side members 2, 3 having inwardly extending flanges 4, 5 respectively at their upper ends. The upper ends 6 of the side members 2, 3 are beveled downwardly from rear to front. The flanges 4, 5 are disposed at a downward inclination from rear to front and their upper faces are flush with the upper ends of the members 2, 3. The support 1 in proximity to its upper end includes a transversely extending cross bar 7 which merges into the inner faces of the side members 2, 3. The bar 7 is of angle-shape cross section to form a horizontal flange 8 and a vertically disposed flange 9, the latter at one end being cut out lengthwise thereof, as at 10. The member 3 is formed with a cutout 11 extending from front to rear thereof at a downward inclination. The cutout 11 opens at the front of member 3. The top and bottom walls of cutout 10 merge into the front ends of the top and bottom walls of cutout 11. The cutouts 10 and 11 provide a clearance for the lower end of the elevator of an upper coin expelling mechanism to be referred to. At the upper end of the outer face of the member 3 there is arranged a laterally disposed supporting plate 12 of angle form consisting of a vertical part 13 and a horizontal part 14. The vertical part 13 is anchored in any suitable manner against member 3.

With reference to Figure 4, the device has as a part thereof a front support 15 of less width and height than the support 1. The support 15 has its top 16 beveled downwardly from rear to front, the bevel being of the same degree as the bevel at the upper end of support 1. The support 15 at one side is cut out as at 17 to form a clearance for a purpose to be referred to.

Mounted upon and secured upon the upper ends of the supports 1 and 15 is a base plate 18, best shown in Figures 1, 2 and 13 which inclines downwardly from rear to front.

With reference to Figures 1, 2, 3, 7 and 9, the device includes four coin storage tubes indicated generally at 19, 20, 21 and 22. The tube 19 is for the storage of quarters and has means associated therewith, which will be hereinafter referred to, for causing the discharge of one quarter therefrom, to form a portion of the change when the latter is to amount to forty-five cents. The tube 20 is arranged in parallel spaced relation to and inwardly of the tube 19 and has the aforesaid means associated therewith for causing the discharge therefrom of four nickels at one time to form the remaining portion of the change when the latter is to amount to forty-five cents. The means referred to is common to the tubes 19 and 20. The tube 21 is for the storage of nickels and has means associated therewith, which will be hereinafter referred to, for causing the discharge therefrom of four nickels at one time when the change is to amount to twenty cents. The tube 22 is for the storage of nickels and has means associated therewith to be herein-after referred to for causing the discharge therefrom of a single nickel when the change amounts to five cents. The tubes 20, 21 and 22 are arranged in a row extending lengthwise with respect to plate 18 and disposed in parallel spaced relation.

The base plate 18 is provided inwardly with respect to the lower end of tube 19 with a circular opening 24 (Figure 9) for the passage of the discharged quarters from the tube 19 into a change delivering or conducting chute to be hereinafter referred to. The base plate 18 is formed in parallel spaced relation to and inward-

ly of the opening 24 with an opening 25 (Figure 9) for the passage of the discharged four nickels from the tube 20 into the change chute. The opening 25 is formed with a pair of oppositely disposed diametrically opposed extensions 26, 27. There is associated with and disposed inwardly of the tubes 21 and 22 openings for the passage of the nickels discharged therefrom through the base plate 18 into the change chute, and the form of each of such openings is similar to the opening 25. That opening which associates with tube 21 is indicated at 28 (Figure 10) and the opening which associates with the tube 22 is indicated at 29 (Figure 13). The openings 25, 28 and 29 are arranged in a row lengthwise of base plate 18 and disposed in parallel spaced relation.

The base plate 18 is formed with a square opening 30 arranged between the openings 28, 29. The base plate 18 is further formed with a row 20 of rectangular slots disposed lengthwise thereof. Each slot is arranged in parallel spaced relation to an opening 25, 28, 29 and 30. With reference to Figure 13, there is shown a slot of the row disposed relative to opening 29 and such slot is designated 31. The other slots of the row are designated 32, 33 and 34 (Figure 22). Connected to or integral with the upper face of base plate 18 and flush with the side edge 35 of the latter, are spaced upstanding parallel guide forming 30 members 36, 37, 38, 39 40 and 41 (Figures 3 and 11.) The guide forming members extend transversely of the plate 18. Each of said members includes a pair of stretches 42, 43 (Figures 7 and 22). The stretch 42 is of greater height 35 includes a pair of stretches 42, 43 (Figures 7 and 22, the stretches 42, 43 of the members 36, 37 coact to provide a guideway 44 which is common to an expelling mechanism for an inserted coin of the value of fifty cents and a change deliverer 40 for discharging a quarter and four nickels; the stretches 42, 43 of the members 38 and 39 coact to provide a guideway 45 which is common to an expelling mechanism for an inserted coin of the value of a quarter and a change deliverer for 45 discharging four nickels; the stretches 42, 43 of members 39 and 40 coact to provide a guideway 46 for an expelling mechanism for an inserted coin of the value of a nickel and for a purpose to be referred to; and the stretcher 42, 43 of the members 40 and 41 coact to provide a guideway 47 which is common to an expelling mechanism for an inserted coin of the value of a dime and a change deliverer for discharging a nickel. The expelling mechanisms and the change deliverers will be presently referred to.

With reference to Figures 13 and 22, the base plate 18 which forms the bottom wall of each of the guideways is beveled downwardly, as at 48, from the outer ends of the slots 31, 32, 33 and 34 60 to the side edge 35 of the plate 18.

With reference to Figures 1, 2, 3 and 4: Anchored upon the upper face of base plate 18 at the upper and lower ends of the latter, and between the lengthwise median and edge 35 of said plate, are aligning angle-shaped brackets 49, 50 respectively. The bracket 49 includes a vertical arm 51 and a horizontally disposed arm 52 extending outwardly from the upper end of arm 51 and beyond the edge 35 of plate 18. The arm 51 is provided at its upper end with a bearing 53. The arm 52 is formed with a pair of spaced bearings 54, 55 and a notch 56 in its top edge. The bracket 50 includes a vertical arm 57 and a horizontal arm 58 extending outwardly from 75

the upper end of arm 57 and beyond the edge 35 of plate 18. The arm 57 is provided at its upper end with a bearing 59. The arm 58 is formed with a pair of spaced bearings 60, 61. The bearings 53, 54 and 55 align with the bearings 59, 60 and 61 respectively. Journaled in the bearing 59 (Figure 2) and extending inwardly and outwardly therefrom is a downwardly inclined primary operating shaft 62 of tubular form having a crank handle 63 secured to its outer end. Journaled in the bearing 53 and extending into the shaft 62 is a downwardly inclined secondary operating shaft 64 provided with a radially disposed pin 65, which extends through a circumferentially disposed slot 66 formed in shaft 62. The pin 65 is arranged outwardly with respect to bracket 50 and coacts with end wall 67 of slot 66 for coupling the shafts 62, 64 to move them in unison after shaft 62 has been partly revolved in a clockwise direction. The pin 65 also coacts with the end wall 67 for moving the shafts in an anti-clockwise direction after the required change has been delivered from the device or an inserted coin expelled from the latter without a change delivery. The shaft 62 has a peripheral shoulder 68. The shaft 64 carries a collar 69 at its upper end. The shoulder 68 coacts with the collar 69 to prevent the lengthwise shifting of the shafts 62, 64 relative to the brackets 49, 50. With reference to Figure 2: Journaled in the bearings 54, 60 is an inner downwardly inclined rock shaft 70. The latter and the shaft 64 constitute actuators for and are common to the expelling mechanisms for inserted coins and which will be hereinafter referred to. The shaft 70 carries stop collars 71, 72 coacting with the brackets 49, 50 to prevent the lengthwise shifting of shaft 70 relative to the brackets. The shaft 70 in close proximity to bracket 50 (Figures 2 and 5) is formed with an outwardly and downwardly extending crank arm 73 engageable by a means to be presently referred to for the purpose of operating shaft 70.

With reference to Figures 1, 2, 5 and 13: Journaled in the bearings 55, 61 is an outer downwardly inclined rock shaft 74 constituting an actuator for a series of pusher mechanisms 75, 76, 77, and 78 respectively for half dollars, quarters, nickels and dimes which are inserted in the device. These mechanisms will be hereinafter referred to. The shaft 74 is provided adjacent its lower end with an inwardly extending crank arm 79 engageable by a means to be referred to for the purpose of operating shaft 74. The inner end of crank arm 79 carries a laterally disposed stub shaft 80 having confined thereon a roller 88. The shaft 74 is provided at its ends with collars 81, 82 which coact with the brackets 49, 50 respectively for arresting the lengthwise movement of the shaft relative to the brackets.

The primary operating shaft 62 is spring controlled, and for such purpose, see Figure 2. A coiled controlling spring 83 is mounted about the shaft between a collar 84 and the bracket 50. The spring is anchored at one end to collar 84 and at its other end to bracket 50. The collar 84 is revolvable about shaft 62 for increasing or decreasing the tension of spring 83. The collar 84 is formed with a circular row of openings 85 (Figure 5) for the passage of a coupling pin 86 to connect it to an actuator element 87 (Figures 2, 5 and 6) for the crank arms 73, 79. The element 87 is fixed to and bodily movable with shaft 62. The latter is of materially less length

than shaft 64, and has its inner end abutted by a stop collar 88 (Figure 2) fixed to shaft 64. The element 87 is positioned on shaft 62 at the inner end of the latter.

With reference to Figures 2, 5, 6 and 13, the actuator element 87 comprises a plate 89 of substantially quadrant-shaped form and is fixed at its upper inner corner upon shaft 62. The plate 89 depends and extends outwardly from shaft 62 and is formed with an arcuate slot 90 for the passage of shaft 70. The plate 89 at its top is provided with a protuberance 91 which extends beyond the outer side edge 92 thereof. The plate 89 in proximity to its top edge 93 has its side edge 92 formed with a cutout 94 having the upper wall 92' of the latter forming an inward continuation of the bottom edge 95 of the protuberance 91. The cutout 94 has extending therethrough the roller 80' of crank arm 79. The crank arms 73, 79 are disposed between plate 89 and bracket 50. The crank arm 73 extends below the crank arm 79. That face of plate 89 which opposes the inner face of bracket 50 at a point below cutout 94 and outwardly with respect to slot 90, has secured thereto a support 96 carrying stub shaft 97 extending towards bracket 50. The stub shaft 97 has confined thereon a roller 98 upon which is seated the crank arm 73. The construction of the actuator element 87 and its arrangement relative to the crank arms 73, 79 provide when shaft 62 is operated in a clockwise direction for the shifting of shaft 70 in a like direction and the shifting of shaft 74 in a counterclockwise direction. When shaft 62 is shifted clockwise, the element 87 is moved in a like direction whereby the roller 98 and the lower wall 99 of cutout 94 will act to elevate in opposite directions the crank arms 73, 79 respectively. The element 87 depends through a slot 100 formed in base plate 18, Figure 2. When the shafts 62 and 64 are coupled together and moved in a clockwise direction, the roller 80' clears the cutout 94 and rides against the curved outer edge 92 of plate 89 as such edge is elevated. The length of crank arm 73 is such that the roller 98 does not clear it when element 87 is elevated.

With reference to Figures 1, 13, 19, 20 and 21, the device includes a coin chute for the purpose of inserting therein coins of greater value than and of a value corresponding to that of the sales price of the article. The chute is permanently open at its upper end. This chute is generally indicated at 101 and is formed of an upstanding curved rear stretch 102 and a downwardly inclined stretch 103 which is arranged over base plate 18. The stretch 102 extends rearwardly and upwardly with respect to the rear end of plate 18. The chute 101 comprises a bottom member 104 of the desired width and length secured upon risers 105 anchored upon the stretches 41 of the guide forming members. Each side marginal portion of the upper face of bottom member 104 has formed integral therewith or connected thereto a row of spaced upstanding ribs 106. The ribs of one row are arranged parallel to the ribs of the other row. The ribs coact to form the upper face of the bottom member 104 with a coin passage 107 lengthwise thereof. The lower end of passage 107 is closed. The ribs are of a width to provide stretches of the passage 107 of different widths. The forward or leading stretch of passage 107, which is at the lower end of the passage 107 is of a width to receive an inserted dime; the stretch following the leading stretch is of a width 75

to receive an inserted nickel; the stretch following the nickel receiving stretch is of a width to receive an inserted quarter, and the remaining stretch is of a width to receive an inserted half dollar. The ribs providing the stretch to receive a quarter constitute stops to arrest the downward movement of the half dollar below the stretch for the latter; the ribs providing the stretch to receive the nickel constitute stops to arrest the downward movement of the nickel below the stretch for the latter and also act to arrest a cent, if it was inserted into the device, from passing from the nickel receiving stretch into the dime receiving stretch. The lower ends of the ribs forming the half dollar receiving stretch are spaced from the upper ends of the ribs forming the quarter receiving stretch to provide a groove for the entrance of a pusher for the half dollar and a discharge outlet for such coin. The lower ends of the ribs forming the quarter receiving stretch are spaced from the upper ends of the ribs forming the nickel receiving stretch to provide a groove for the entrance of a pusher for the quarter and a discharge outlet for such coin. The lower ends of the ribs forming the nickel receiving stretch are spaced from the upper ends of the ribs forming the dime receiving stretch to provide a groove for the entrance of a pusher for the nickel and a discharge outlet for such coin. The lower ends of the ribs forming the dime receiving stretch are spaced from the lower end closure of the passage to provide a groove for the entrance of a pusher for the dime and a discharge outlet for such coin. The arrangement of a stretch, groove and outlet would be as shown in Figure 13 and wherein the stretch, groove and outlet are designated 108, 108' and 109 respectively. Each of the stretches referred to has the bottom wall thereof transversely grooved, as at 109' (Figure 20) and also lengthwise grooved at the bottom of outlet 108, as at 110, Figure 13.

The chute 101 also includes a top member 111 (Figures 13, 19 and 20) of the same width and length as bottom member 104. The top member 111 is secured upon the rows of ribs and forms a top closure for the coin passage. The inner side of top member 111 centrally with respect to each outlet 109 is cutout as at 112, Figure 13 to provide a clearance.

The manner in which the interior of chute 101 is formed is indicated by dotted lines Figure 2.

The coin pusher mechanisms are of like construction, and the description of one will apply to the other. Each of said mechanisms, and with reference to Figures 1, 13, 19 and 20, includes a slidable pusher 113 formed on its lower face with a tongue 114, for seating in a groove 109'. The pusher 113 extends into a stretch 108 through a groove 108'. The function of pusher 113 is to shift the coin from stretch 108 through the outlet 109. The pusher 113 travels in a direction transversely of the chute 101. The length of the pusher 113 is greater than the width of chute 101 and permanently projects from the outer side of the latter. The outer end of the pusher 113 is formed with an opening 115', into which extends the angularly disposed reduced lower end 116' of an operating arm 117 which is fixed at its upper end to and depends at an outward inclination from the shaft 74. On the operation 75 of the latter in a counterclockwise direction, the

pusher 113 will be moved inwardly and transversely of chute 101 to discharge the coin from its receiving stretch, and when shaft 74 is moved clockwise, the pusher 113 will be shifted outwardly to an extent to prevent it interfering with a coin entering its receiving stretch. 5

The device includes expelling mechanisms for the inserted coins and the number of said mechanisms corresponds to that of the pusher mechanisms for the inserted coins. Each expelling 10 mechanism is associated with a pusher mechanism and is coupled for operation by the pushed coin as the latter is being shifted by a pusher mechanism from the coin chute. As the expelling mechanisms are of like construction, but 15 one will be described, as the description of one will apply to the other. The expelling mechanisms are generally indicated at 114, 115, 116 and 117 for the half dollars, quarters, nickels and dimes respectively inserted in the coin chute 102. 20

With reference to Figures 2 and 13, but more especially to Figure 13, each expelling mechanism includes a pair of spring controlled couplers 118, 119 for detachably connecting it successively to the shafts 70, 64 respectively; a pair of sleeves 25 120, 121 loosely mounted on shafts 70, 64 respectively and detachably connected successively with the shafts 70, 64 respectively by the couplers 118, 119 respectively to provide for the moving of the sleeves bodily with the shafts. The shafts 70, 64 30 are formed with sockets 122, 123 respectively to receive the couplers 118, 119 respectively. There is associated with the couplers 118, 119 shifting means 124, 125 therefor respectively. The coupler 118 is arranged below shaft 70. The coupler 119 35 is arranged above shaft 64.

The sleeve 120 has an opening 126 for aligning with socket 122. The normal position of the latter is at the bottom of shaft 70. The sleeve 121 has an opening 127 for aligning with socket 123. 40 The normal position of the latter is at the top of shaft 64. The opening 126 is of two different diameters, the smaller of which is to register with socket 122. The opening 127 is of two different diameters, the smaller of which is to register with the socket 123. The walls of the openings 126, 127 are shouldered as at 128, 129 respectively. 45

The coupler 118 is for extension through opening 126 to engage in socket 122 to couple shaft 50 70 and sleeve 120 together. The coupler 119 is for extension through opening 127 to engage in socket 123 to couple shaft 64 and sleeve 121 together. The coupler 118 comprises a headed pin 130 and secured to and projecting from the outer end of 55 the head of pin 130 is a lateral arm 131 constituting an abutment for engagement by the shifting means 124 to move pin 130 vertically into socket 122 and to hold the pin in coupling position for the desired period. The means 124 consists of a 60 cylinder 132 (Figure 13) positioned against the inner side of a bar 133 anchored at its ends upon blocks 134 (Figure 1) secured upon chute 101 and extending inwardly therefrom. The cylinder 132 is open at its bottom and has its top formed with 65 an inwardly extending annular flange 135. Movable lengthwise of and within cylinder 132 is a spring controlled plunger 136, which extends through flange 135 for the purpose of engaging 70 arm 131, whereby when the plunger 136 moves upwardly, the pin 130 and arm 131 will be moved in a like direction resulting in pin 130 coupling sleeve 120 and shaft 70 together when the opening 126 registers with socket 122. The plunger 136 75

normally depends below the bottom of cylinder 132, through cutout 112 and into a stretch 108. The lower end of plunger 136 has a beveled surface 137 positioned in the path of the inserted coin 5 to be shifted by a pusher. The arrangement referred to provides for the coin which is to be discharged from chute 101, acting upon plunger 136 raising it to an extent to provide for pin 130 coupling sleeve 120 and shaft 70 together, whereby 10 shaft 70 revolves, sleeve 120 will be carried therewith. The cylinder 132 is maintained in position by a clamping member 138 (Figure 13) bearing thereagainst and against the inner side of bar 133. The clamping member 138 and bar 133 are secured together by clamping screws 139 (Figure 13).

The coupler 119 comprises an upstanding internally shouldered cylinder 140 (Figure 13), which threadedly engages with that portion of 20 greater diameter of the wall of opening 127. The cylinder 140 projects from sleeve 121 and has arranged therein a peripherally shouldered spring controlled shiftable plunger 141, of a length to extend beyond each end of the cylinder 140. The 25 plunger 141 when shifted inwardly extends into the socket 123 and couples sleeve 121 and shaft 64 together as they will revolve in unison. The shifting means 125 consists of a compressing arm 142 (Figures 2 and 13) substantially of Z-form 30 having its upper stretch 143 adapted to apply pressure against the outer end of plunger 141. Operated from the sleeve 120 is an angle-shaped member 144 (Figure 13) including a horizontal stretch 145 formed with a convexo-concave portion seated on and fixedly secured to sleeve 120 35 as at 146. The member 144 also includes an upstanding stretch 146, formed intermediate its ends with a slot 147, through which extends the reduced outer end 148 of the lower stretch 149 40 of the arm 142. The end 148 of arm 142 is pivotally connected to stretch 145, as at 150. The stretch 145 is also seated upon and extends outwardly from a supporting bar 151 which is mounted and secured at one end thereof in the notch 45 46 (Figure 2) and has its other end formed with an inward extension 152 anchored to a standard 153 (Figure 1). The stretch 145 inwardly of the bar 151 (Figure 2) carries a depending screw 154 (Figures 2 and 13) to which is secured the upper 50 end of a coiled controlling spring 155. The lower end of the latter is anchored to a bar 156 secured upon the blocks 134. When the sleeve 120 is moved in a clockwise direction by shaft 70 it will carry the member 144 in a like direction 55 against the action of its controlling spring. As member 144 moves in the direction stated, the pressure applying arm 142 will be carried therewith, whereby it will act upon plunger 141 and compress the latter to an extent to cause it to 60 couple sleeve 121 with shaft 64 when opening 127 registers with socket 123, whereby the shaft 64 and sleeve 121 will revolve in unison.

Each expelling mechanism also includes a combined spring controlled, shiftable coin holder, coin lowerer and carrier means which receives the coin discharge from the chute 101 by a pusher. The said means is operated from sleeve 120 to perform its coin holding, lowering and carrying function to position the coin at the 65 point from which it is to be expelled from the expelling mechanism. With reference to Figures 13 to 18, the said means includes a yoke-shaped element or carrier 167 slidably mounted in one of the guideways, and as shown by way of 70 example in Figure 13, it is arranged in guideway 75

47. The element 157 has its bottom formed with a guide piece 158 positioned in slot 31. A tubular extension 159 depends from guide piece 158. The lower end of extension 159 is restricted (Figure 13). The bottom of element 157 has its upper 5 face cut away to form a reduced portion 160 which is arranged over the guide piece 158. The element 157 is formed with an opening 161 registering with an opening 162 formed in the guide piece 158. The reduced portion 160 constitutes a 10 seat for a carrier plate 163 secured upon the upper end of a vertically movable spring controlled peripherally shouldered elevator 164 which passes through the openings 161, 162 and the extension 159. The elevator 164 is of a length to normally 15 extend above the element 157 to dispose the carrier plate 163 in position to receive the inserted coin which is discharged from chute 101 by a pusher. The upper face of plate 163 has pointed 20 barbs 165 to prevent the slipping of the coin when the elevator is lowered. The element 157 at its rear and spaced above the bottom thereof has secured therein a transversely extending pivot bar 166 (Figures 13 and 15) upon which is pivotally mounted the inner end of a holding arm 167 25 which coacts with the plate 163 to maintain the coin on the latter when the elevator 164 is lowered. The arm 167 further functions in connection with a depressor to be referred to, for lowering the elevator 164 to an extent to provide for 30 the positioning of plate 163 upon the reduced portion 161 of the bottom of element 157 and for shifting the element 157 in an outward direction in guideway 41. A controlling spring 168 is provided for arm 167. The latter is of a length to 35 extend over plate 163, and has its lower face formed with pointed barbs 170, which coact with the barbs 165 to prevent the shifting of the coin from off plate 163 when the elevator is lowered and element 157 shifted in the direction as stated. 40 The arm 167 is bifurcated and apertured at its rear end, as at 170, 170' respectively and has its upper face at its outer end formed with a pair of parallel spaced lugs 171 carrying a shaft 172 provided with a roller 173 (Figures 13 and 18). The 45 roller 173 provides an abutment. That end of the arm 167 carrying the roller 173 is arranged in the path of a curved depressor 174, which is pivotally supported at its upper end, as at 175, from the inner side of sleeve 120. By this arrangement when sleeve 120 is revolved in a clockwise direction, the depressor 174 will be carried therewith and lowered to engage and move the outer end of arm 167 downwardly to engage the coin on plate 163. The depressor 174 50 will further act, during the clockwise movement of sleeve 120, to continue to move the outer end of arm 167 downwardly whereby a like movement will be had to the elevator and in connection with arm 167 shift the element 157 in a direction towards the chute 100. The depressor 174 will act to an extent upon elevator 164 to cause the seating of the plate 163 upon the reduced portion 160 55 against the action of the controlling spring of the elevator. The purpose of the foregoing operation is to dispose the inserted coin in a position to be expelled into the conducting off chute 100. The latter will be hereinafter referred to.

Each expelling mechanism also includes a means for expelling the coin after the latter has 70 been moved to the position aforesaid, and with reference to Figures 13 to 16, the said means includes a slidably expeller 176 which is slidably mounted on the bottom and travels in grooves 177 formed in the inner faces of the side walls of ele- 75

ment 157. The expeller 176 is cut out at its outer portion, as at 178 to partly surround the coin on plate 163, and to form an edge portion 179 to engage the coin, whereby on the outward sliding of the expeller 176, the coin will be expelled from within the guideway into the conducting off chute 180 (Figure 13). The operation of the expeller 176 is had through the medium of a pair of spaced curved shifters 181, which are connected to a pivot bar 182 suspended from the rear end of the expeller 176, as at 183. The shifters 181 are pivotally connected, as at 184 to the lower end of an upstanding actuating member 185, which is secured at its upper end as at 185' to and is operated from the sleeve 121. When the latter is revolved by shaft 64 in a clockwise direction, the member 185 is carried therewith in a like direction, and provides for the moving of the shifters 181 towards the outer end of element 157 whereby the expeller 176 will be carried therewith in a like direction to an extent to expel the coin from off of plate 163.

With reference to Figures 7 to 13, the device includes a set of change deliverers as shown three in number, generally indicated at 186, 187 and 188. The change deliverer 186 acts to deliver simultaneously a quarter and four nickels respectively from the coin storage tubes 19, 20. The change deliverer 187 acts to deliver simultaneously four nickels from the coin storage tube 21 and the change deliverer 188 acts to deliver a nickel from coin storage tube 22. The deliverers 186, 187 and 188 are connected to the inner ends of and are operated by the expelling mechanisms 114, 115 and 117 respectively. The deliverers are slidably mounted on the base plate 18 and are positioned below and normally extend beyond the lower ends of the coin storage tubes. With reference to Figures 9 and 11, the deliverer 186 consists of a slide 189. The latter is integral with the inner end of the bottom of the element 157 of the expelling mechanism 114. The slide 189 is arranged below the tubes 19 and 20 and is formed of three stretches 190, 191 and 192. The stretch 190 is lengthwise slotted, as at 193 and is integral at one end with the element 157. The stretch 190 at its other end merges into one end of stretch 191, the latter being of greater height than stretch 190. The stretch 190 is formed with an opening 194 of a depth to receive four nickels and is also formed with a lengthwise slot 195 which intersects opening 194, as well as forming a continuation of slot 193. The stretch 191 at its other end merges into one end of the stretch 192. The latter is of less height than stretch 190 and is formed with an opening 196 of a depth to receive a quarter. The normal position of slide 189 is as shown in Figure 9 with the openings 194 and 196 arranged at the lower ends of tubes 20 and 19 for receiving four nickels and a quarter respectively. When element 157 of the expelling mechanism 114 is moved in a direction toward the chute 180, the slide 189 is carried thereby whereby the four nickels and the quarter are transported to the openings 25 and 24 respectively, and discharged through said openings into the change delivering chute to be referred to. As the slide 189 moves in the direction as stated, the lower ends of the tubes 19 and 20 are closed.

With reference to Figures 10 and 12, the change deliverer 187 consists of a slide 197 arranged below tube 21 and formed of a pair of stretches 198, 199. The latter is of less height than the former and has one end thereof integral

with the inner end of the bottom of the element 157 of the expelling mechanism 115. The other end of stretch 199 merges into one end of stretch 198. The stretch 198 is lengthwise slotted as at 200. The stretch 198 is formed with an opening 201 of a depth to receive four nickels from tube 21. The stretch 198 is also formed with a lengthwise slot 202 which intersects opening 201 and forms a continuation of slot 200. When element 157 of the expelling mechanism 115 is moved in a direction towards chute 180, the slide 197 is carried thereby whereby the four nickels are transported to the opening 28 and discharged through the latter into the change delivery chute. As the slide 197 moves in the direction as stated, the lower end of the tube 21 is closed.

With reference to Figure 13, the change deliverer 188 consists of a slide 203 arranged below tube 22 and formed with an opening 204 to receive a nickel from tube 22. The slide 203 is integral at one end with the inner end of the bottom of element 157 of the expelling mechanism 117 and is also formed with a lengthwise slot 205 intersecting opening 204. When element 157 of the expelling mechanism 117 is moved towards chute 180, the slide 203 is carried therewith, whereby the nickel is transported to the opening 29 and discharged through the latter into the change delivery chute. As the slide moves in the direction as stated, the lower end of tube 22 is closed.

The element 157 of each expelling mechanism is formed at its rear end with a pair of shoulders 206 (Figure 15) which coact with the expeller 176 for the purpose of shifting the element 157 to its normal position. The coaction of the parts referred to with respect to the expelling mechanisms 114, 115 and 117 also provide for restoring the change deliverers 186, 187 and 188 respectively to normal position. Each expelling mechanism includes a controlling spring 207 (Figures 2, 3 and 4) for an expeller 176 and which acts to move the latter inwardly to abut the shoulders 206 whereby the element 157 will be carried with the expeller 176, due to the pulling action of the controlling spring. The springs 207 are secured at one end with the lower ends of the actuating members 185, as at 208. As the change deliverers 186, 187 and 188 are connected to the elements 157 of the expelling mechanisms 114, 115 and 117, it follows that when the said elements 157 are moved inwardly due to the coacting of the expellers 176, shoulders 206 and controlling springs 207 of mechanisms 114, 115 and 117 the change deliverers will be restored to their normal position.

With reference to Figures 2, 7, 9, and 13, there is arranged upon, as well as being secured to the stretches 43 of the guide forming members a plate 209 provided with a lateral extension 210 at one end. The plate 209 functions to retain the change deliverers and a slotted slide 211 extended from the element 157 of the expelling mechanism 116 upon the base plate 18. The extension 210 is of greater height than the body of the plate 209, is apertured as at 212, and functions to retain that portion of change deliverer 186, which associates with tube 19, upon the base plate 18. The lower end of tube 19 is secured in the opening 212 and is flush with the lower face of extension 210. The body of plate 209 functions to retain that portion of the change deliverer 186 which associates with the tube 20 upon base plate 18 and further functions to retain the change deliverers 187, 188 and the slide 211 upon base plate 18. The

body of plate 209 is formed with three openings 213, 214 and 215 in which the lower ends of the tubes 20, 21 and 22 respectively are secured. The lower ends of the tubes 20, 21 and 22 are flush with the inner face of the body of the plate 209. The inner portion of plate 209 is formed with a set of spaced notches 216, 217, 218, and 219. The notch 218 is arranged between and in parallel spaced relation to the notches 217, 219.

10 Each of the tubes 20, 21 and 22 has clamped thereto in encompassing relation and intermediate the ends thereof, a support 220 formed with a lateral apertured extension 221 at one side. The body of the support anchored to tube 21 is not shown, but the lateral extension is. Fixed in the extensions 221 is a shaft 222 upon which is loosely mounted the upper ends (Figure 2) of a set of spaced hangers 223, 224, 225, 226 extending downwardly through the notches 216, 217, 218 and 219 respectively. The hangers 223, 224 and 226 extend through the change deliverers 186, 187 and 188 and are operated from the coins carried by said deliverers. The hanger 225 extends through the slide 211 and is operated by the outer wall of the aperture in slide 211. The hangers are independently shiftable. The hangers 223, 224 and 226 are arranged in the path of the coins carried by the change deliverers. The hanger 225 is arranged in the path of movement of slide 211. Pivotaly connected to the lower end of each hanger and arranged below the base plate 18 is a shover 227 (Figure 13) for the chute 180. Supporting and guiding means 228 (Figure 13) common to all of the shovers is arranged below, extends lengthwise of and is secured to the base plate 18 adjacent the edge 35 thereof. The shovers 227 when moved to active position extend beyond the means 228. The chute 180 has its upper end supported upon and pivotally connected, as at 229 to the part 14 of the plate 12. The inner side wall 230 (Figure 13) of chute 180 is of less height than the outer side wall to provide for the chute 180 to partly extend under the base plate 18. The chute 180 has associated therewith a controlling means 231 (Figure 3) which is anchored at one end to a pin 232 depending from the lower portion of the chute. The other end of spring 231 is anchored to a pin 233 depending from the supporting and guiding means 228. The shovers 227 have their outer ends positioned in proximity to the wall 230 of chute 180. The latter has its lower portion 234 (Figure 23) extending inwardly at an outward inclination. The function of chute 180 is for the purpose of conducting the expelled coins to a receiver 235 (Figure 23), but when the device is operated after the insertion of a coin of greater value than the sales price of the article and cannot make change due to the fact that the coin tubes are empty, the chute 180 functions to deliver such coin when expelled to the change delivering chute 236 (Figure 23). The normal position of the chute 180 relative to the chute 236 is as shown in Figure 23 whereby the portion 234 of chute 180 is arranged for discharging into chute 236. The latter has its inner side wall 237 cut out at 238 for the purpose of having the lower end of chute 180 to extend into and be supported by wall 237, whereby if a coin has been expelled into chute 180 and the latter is in normal position, the coin will be discharged into chute 236. The chute 180 is held in its normal position by the spring 229, and is shifted therefrom by a shover 227 when the latter is moved by the hanger 223 with which it is associated. The hanger 223 is

operated by the four nickels carried by change deliverer 186; hanger 224 by the four nickels carried by change deliverer 187; hanger 225 by the wall of the aperture in slide 211 and hanger 226 by the nickel carried by change deliverer 188. 5 The hangers are returned to normal position by the change deliverers and the slide 211 and which carry the shovers 227 therewith permitting of the chute 180 to assume its normal position. The chute 236 is secured against the lower face of 10 the base plate 18 below the openings 24, 25, 28 and 29, extends forwardly from support 15 and through the cutout 17 for discharge into a cup 238' to be hereinafter referred to. The chute 236 includes the stretches 239, 240, 241 and 242 (Figure 15). The stretches 239, 240 and 241 are of uniform and like width. The stretch 242 is wider than the other stretches and includes a portion of gradually decreasing width merging into the stretch 241. The stretch 240 is outwardly inclined with respect to stretch 239 and merges at its inner end on the outer end of stretch 241. The stretch 239 is offset with respect to stretches 241, 242 and extends through the cutout 17.

With reference to Figure 2: Secured upon the 25 body of the plate 209 is a strap 243, provided with anchoring means 244 for the outer ends of the controlling springs 207.

With reference to Figures 2 and 13, the device includes a group of coupled spaced guide and 30 arrestor bars 245 disposed lengthwise thereof for the depressors 174. The group of bars 245 is anchored to the brackets 49, 50.

With reference to Figures 7, 9 and 10, the coin storage tubes 19, 20, 21 and 22 are provided at 35 their upper ends with external collars 246, 247, 248 and 249 respectively. The collars are flush with the upper ends of the tubes. Anchored upon the collar 246 is a square plate 250 provided with an opening 251 having its edges registering 40 with the inner face of tube 19. Secured upon plate 250 is a plate 252 of half the size of plate 250. The plate 252 is formed with a semi-circular opening 253 having its edge registering with the edge of opening 251. The plate 252 is flush with 45 plate 250. Secured upon plate 252 is a deflector 254 (Figures 5 and 6) formed of a horizontally disposed stretch 255 and an upstanding stretch 256 disposed diametrically with respect to the upper end of tube 19. The deflector 254, when 50 tube 19 is being filled with quarters, functions to direct the latter into the tube 19 from the upper end thereof.

With reference to Figures 2 and 7: Secured upon the collars 247, 248 and 249 is an oblong 55 plate 257, formed with openings 258, 259 and 260 registering respectively with the inner faces of the tubes 20, 21 and 22. The plate 257 is formed with a raised portion at the leading side of opening 259 to provide a cam surface 261 for a purpose to be referred to. Secured upon the plate 257 is an oblong plate 261 formed with an elongated slot 262 corresponding in width to the diameter of any one of the openings 258, 259 and 260. The width of slot 262 however is such as to permit of 60 the travel of nickels therethrough to enter the tubes 20, 21 and 22. The end wall 263 of slot 262 registers with the follower side of the edge of opening 260. The end wall 264 of slot 262 is spaced adjacent the leading side of the edge of opening 258 and is beveled. The end 265 of plate 261 is slightly upturned. Secured upon and of less length than the plate 261, is an oblong plate 266, having the end 267 thereof upturned, spaced from and opposing the end 265 of plate 261. The 75

plates 257, 261 and 266 coact to provide a coin filling chute 268 for the tubes 20, 21 and 22. The mouth of chute 268 is indicated at 269. It will be assumed that when tube 21 is filled with nickels, the edge of the uppermost nickel would slightly extend above the edge of opening 259 and the leading side of the latter was not raised. Under such conditions if tube 22 were to be filled the raised edge of the nickel referred to would arrest the travel of the nickels toward tube 22. By providing the cam surface 260 the objection referred to its obviated, as the nickels traveling towards tube 22 would be elevated above and clear the edge of the uppermost nickel of the stack of nickels within tube 21.

The receiver 235 is to be arranged within a forwardly extending angle-shaped bracket 269 which is anchored to and extends forwardly from support 15.

20 The device includes means for forcing an inserted cent from the chute 101. With reference to Figure 19, the top member 111 of chute 101 is formed with an opening 270 and a slot 271 leading from the outer side of said opening 270 to the outer edge of member 11. Operating in the slot 271 is a pusher 272 having a beveled edge 273 for the purpose of engaging and expelling the cent out of chute 101 through and clear opening 270. The pusher 272 is carried by and operated from the pusher 113 of the pusher mechanism 11 for the nickels. The diameter of the cent will prevent it from passing into that stretch of the chute 101 for the reception of the dimes.

With reference to Figure 24, the various elements and mechanisms of the device are arranged within a housing 274 having one of its side walls hinged to constitute a door and which carries a lock for maintaining it in closed position. The hinged wall and lock are not shown, as the construction and arrangement thereof is obvious. The front wall 275 of housing 274 is slotted at its lower portion, as at 276 and cup 238' is arranged at slot 276. The front wall 275 is also formed with an opening 277 for the passage of the primary operating shaft 62 with handle 63 disposed outwardly of wall 275. The top wall 278 of housing 275 is formed with slots 279, 280 and 281. The slot 279 is provided for the insertion of a coin into the chute 101; the slot 280 for filling tube 19 with quarters; and slot 280 for supplying nickels to the chute 268 for the purpose of filling the tubes 20, 21 and 22.

The operation of each of the several mechanisms and change deliverers has been referred to, but with respect to a general operation of the device it will be stated that the expelling mechanisms and change deliverers are not operated unless a coin of the same value and of greater value than a nickel is inserted into chute 101. The pusher mechanisms may be operated at any time. Now it will be assumed that a coin of the value of a half dollar is inserted in chute 101 and that it passes to the lower end of that stretch of chute 101 which is to receive the coin. The operator then shifts the handle 63 in a clockwise direction causing the operation of shaft 62 which will provide for the moving of shaft 74 in an anti-clockwise direction causing the operation of all of the pusher mechanisms, but the pusher mechanism 75 will act to push the coin from the chute 101 in a direction to provide for the coupling of sleeve 120 of the expelling mechanism 114 to shaft 70 which is moving in a direction corresponding to the direction of movement of shaft 62. When sleeve 120 of the expelling mechanism is coupled

to shaft 70 it will be carried with the latter causing thereby the coupling of sleeve 121 to shaft 64 and at this point shafts 62 and 64 will move in unison. The sleeve 120 functions to provide for the holding of the coin upon the elevator and the shifting of element 157 of mechanism 114 in a direction towards the chute 180. As element 157 moves in a direction towards chute 180, it will move the slide 189 of change deliverer 186 to an extent and in a direction to provide for the discharge of a quarter and four nickels into the change conducting chute 236. After the element 157 has been shifted in a manner as stated, the sleeve 121 provides for the ejector 176 of mechanism 114 to expel the coin into the chute 180. As the slide 189 moves in the direction aforesaid, the nickels carried by such slide will shift the lower end of the hanger 223 in a direction towards chute 180. Such movement of hanger 223 will provide for the shover 227, connected to the lower end thereof, to engage the chute 180 and swing the latter outwardly on its pivot to an extent whereby chute 180 will conduct the coin to the receptacle 235. When the depresser 174 is moved clear of or releases arm 167, the plate 163 will rise with arm 167, expeller 157 will pass under arm 167 in a forward direction and the depressed end of the latter will elevate due to the action of controlling spring 169, at which time the coin will be expelled from off of the elevator by the expeller 176. The latter is moved forwardly against the action of spring 237.

The sleeves 120 and 121 are uncoupled from shafts 70, 64 respectively when pressure is relieved upon the means 124 and upon coupler 119, after which as each of the sleeves are spring controlled they are returned to their normal position, as when uncoupled they are free to revolve about their shafts. The shafts 62, 64, 70 and 74 are returned to their normal position by the action of the controlling spring 83. Pressure is relieved upon the coupler 119 when the arm 131 clears the plunger 136 due to the coupler 119 being carried by the sleeve 120, when the latter is revolved to an extent to clear the said plunger. Pressure is relieved upon the coupler 119 when the sleeve 121 is revolved by shaft 64 to an extent to clear the means 125. Immediately after the release of the sleeves 120, 121 the shafts 64, 70 and 74 as well as shaft 62 are returned to normal position.

What I claim is:—

1. In a change making device, an inserted coin receiving chute having a normal open intake end and being closed at its other end, said chute having its inner side provided with spaced outlets for the discharge of the coins inserted therein, pusher mechanisms extending into said chute from the outer side of the latter, operating transversely of said chute and coacting with said outlets for discharging the inserted coins, a bodily shiftable pivoted spring controlled coin conducting chute bodily slidably spring and inserted coin controlled expelling mechanisms for receiving the inserted coins from the receiving chute and for expelling them into the conducting chute, change deliverers connected to, bodily movable with and operated from all but one of said expelling mechanisms for transporting the change to be delivered, a change delivering chute common to and for receiving the change from said deliverers, said conducting chute normally opening into the discharge end of said delivering chute, operating means for the pusher mechanisms and the expelling mechanisms, and conducting chute shifting means arranged in the path of the change being

transported by said deliverers and shifted by the change in the deliverers prior to the reception of the change by the delivery chute for shifting said conducting chute from its normal position.

5. 2. In a change making device, an inserted coin receiving chute having a normal open intake end and being closed at its other end, said chute having its inner side provided with spaced outlets for the discharge of the coins inserted therein, pusher mechanisms extending into said chute from the outer side of the latter, operating transversely of said chute and coacting with said outlets for discharging the inserted coins, a bodily shiftable pivoted spring controlled coin conducting chute bodily slidable spring and inserted coin controlled expelling mechanisms for receiving the inserted coins from the receiving chute and for expelling them into the conducting chute, change deliverers connected to, bodily movable with and operated from all but one of said expelling mechanisms for transporting the change to be delivered, a change delivering chute common to and for receiving the change from said deliverers, said conducting chute normally opening into the discharge end of said delivering chute, operating means for the pusher mechanisms and the expelling mechanisms, conducting chute shifting means arranged in the path of the change being transported by said deliverers and shifted by the change in the deliverers prior to the reception of the change by the delivery chute for shifting said conducting chute from its normal position, and means operated from the said one of said expelling mechanisms for operating said conducting chute shifting means when the inserted coin which controls the said one mechanism is of a value requiring no change.

3. In a change making device for delivering change therefrom of a value equal to that between a predetermined value and the value of coins inserted therein of different greater values than said predetermined value, a slideable change deliverer having means for simultaneously transporting change consisting of a group of superposed coins of like value and a single coin of a greater value than any one of the coins of the group to spaced points for simultaneous discharge of the coins of said group and single coin, a slideable change deliverer for simultaneously transporting change consisting of a group of superposed coins of like value to a single point for simultaneous discharge of the coins of such group, a slideable change deliverer for transporting change consisting of a single coin to a point of discharge, a set of slideable spring controlled inserted coin expelling mechanisms, the said mechanisms, other than one thereof being associated with and selectively operating said deliverers, an actuating structure for and common to said mechanisms, each of said deliverers being fixed to and bodily moving with its associated expelling mechanism, each of said expelling mechanisms for receiving and expelling an inserted coin of a different value than that received and expelled from any one of the other expelling mechanisms and including a spring controlled normally inactive operating mechanism therefor and a controlling means arranged in the path of and movable to active position by the inserted coin which is to be received and expelled thereby to provide for the coupling of said operating means to said structure, pusher mechanisms operated from said actuating structure for pushing the inserted coins into said expelling mechanisms to make said controlling means active, a coin conducting chute ar-

ranged relatively to and common to said expelling mechanisms for receiving the inserted coins therefrom, said chute being pivotally mounted, shiftable relative to said expelling mechanism and normally in non-shifted position for returning the inserted coins, and means for shifting said chute from normal for retaining the inserted coins. 5

4. A change making device constructed in accordance with claim 3 having each expelling mechanism provided with a carriage, a vertically movable elevator connected to the latter, and a slideable expeller mounted in and slideable relative to the carriage, said carriage, elevator and expeller being bodily movable together.

5. A change making device constructed in accordance with claim 3, the combination therewith of means for positioning inserted coins of different values at a point to be engaged by said pusher mechanisms, said means having grooves for the entrance therein and outlets therefrom of coins 20 acted upon by said pusher mechanisms.

6. A change making device constructed in accordance with claim 3, the combination therewith of a pair of coin storage tubes associated with that deliverer for transporting a single coin and 25 a group of coins, a coin storage tube associated with each of the other deliverers, and a change delivering chute associated with said deliverers and having a cutout in one side for the passage therein of the discharge end of said shiftable 30 chute.

7. A change making device constructed in accordance with claim 3, the combination therewith of means for positioning inserted coins of different values at a point to be engaged by said pusher 35 mechanisms, said means having grooves for the entrance therein and outlets therefrom for the coins acted upon by said pusher mechanisms, a pair of coin storage tubes associated with that deliverer for transporting a single coin and a 40 group of coins, a coin storage tube associated with each of the other deliverers, a change delivering chute associated with said deliverers, and said conducting chute for the coins received and expelled by said expelling mechanisms being 45 spring controlled.

8. In a change making device, bodily shiftable spring and inserted coin controlled expelling mechanisms for receiving and expelling coins inserted into the device, means for positioning inserted coins relative to said expelling mechanisms, pusher mechanisms extending into said means for discharging the inserted coins laterally therefrom into said expelling mechanisms, change deliverers connected to, bodily movable with and 50 operated from all, but one of said expelling mechanisms transporting change to be delivered, a spring controlled actuating structure for said expelling mechanisms, means carried by said structure for operating said pusher mechanisms, a 55 shiftable inserted coin returning and retaining chute for receiving the coins from the expelling mechanisms and normally in non-shifted position for returning the coins, and means for shifting the chute from normal for retaining the inserted coins. 65

9. In a change making device, bodily shiftable spring and inserted coin controlled expelling mechanisms for receiving and expelling coins inserted into the device, means for positioning inserted coins relative to said expelling mechanisms, pusher mechanisms extending into said means for discharging the inserted coins laterally therefrom into said expelling mechanisms, change deliverers connected to, bodily movable 70 75

with and operated from all, but one of said expelling mechanisms transporting change to be delivered, a spring controlled actuating structure for said expelling mechanisms, means carried by said structure for operating said pusher mechanisms, a stationary chute for delivering the change, a pivoted chute for conducting off the expelled coins, said conducting chute having its discharge end normally opening into said change delivery chute, and conducting chute shifting means arranged in the path of the change being transported by said deliverers and shifted by the change in the deliverers prior to the reception of the change by the delivery chute from shifting the conducting chute from its normal position.

10. In a change making device, bodily shiftable spring and inserted coin controlled expelling mechanisms for receiving and expelling coins inserted into the device, means for positioning inserted coins relative to said expelling mechanisms, pusher mechanisms extending into said means for discharging the inserted coins laterally therefrom into said expelling mechanisms, change deliverers connected to, bodily movable with and operated from all, but one of said expelling mechanisms transporting change to be delivered, a spring controlled actuating structure for said expelling mechanisms; a spring controlled shiftable inserted coin returning and retaining conducting chute common to the expelling mechanisms and normally in non-shifted position for receiving an inserted coin, for returning the latter, a conducting chute shifting means for moving the latter from normal for retaining an inserted coin, means carried by said structure for operating said pusher mechanisms, and means operated from the said one of said expelling mechanisms for operating said conducting chute shifting means when the inserted coin which controls the said one mechanism is of a value requiring no change.

11. In a change making device for delivering change therefrom of a value equal to that between a predetermined value and the value of coins inserted therein of different greater values than said predetermined value, a slidable change deliverer having means for simultaneously transporting change consisting of a group of superposed coins of like value and a single coin of a greater value than any one of the coins of the group to spaced points for simultaneous dis-

charge of the coins of said group and single coin, a slidable change deliverer for simultaneously transporting change consisting of a group of superposed coins of like value to a single point for simultaneous discharge of the coins of such group, a slidable change deliverer for transporting change consisting of a single coin to a point of discharge, an actuating structure for and common to said deliverers and including a set of coupling mechanisms each having its operation controlled by the diameter of an inserted coin for selectively connecting a deliverer to said actuating structure to be operated by the latter, and pusher mechanisms operated from said actuating structure for pushing the inserted coins inwardly to make the coupling mechanisms active.

12. In a change making device for delivering change therefrom of a value equal to that between a predetermined value and the value of coins inserted therein of different greater values than said predetermined value, a slidable change deliverer having means for simultaneously transporting change consisting of a group of superposed coins of like value and a single coin of a greater value than any one of the coins of the group to spaced points for simultaneous discharge of the coins of said group and single coin, a slidable change deliverer for simultaneously transporting change consisting of a group of superposed coins of like value to a single point for simultaneous discharge of the coins of such group, a slidable change deliverer for transporting change consisting of a single coin to a point of discharge, an actuating structure for and common to said deliverers and including a set of coupling mechanisms each having its operation controlled by the diameter of an inserted coin for selectively connecting a deliverer to said actuating structure to be operated by the latter, and pusher mechanisms operated from said actuating structure for pushing the inserted coins inwardly to make the coupling mechanisms active, an inserted coin conducting chute having spaced means for the passage therefrom in a horizontal direction towards said coupling mechanisms of the inserted coins, said means being formed with provisions for arresting the travel of the inserted coins in said chute, and said pusher mechanisms operating through said spaced means.

MORRIS DORMAN.
